FRICTION DRAFT GEAR

Henry A. Herndon, Chicago, Ill., assignor to The Bradford Patents Corporation, New York, N. Y., a corporation of Delaware

Application September 28, 1928
Serial No. 309,005

10 Claims. (Cl. 213—33)

My invention relates to friction draft gears and has for its general object the provision of an efficient draft gear capable of developing a high resistance during closure and insuring the return 5 of the members to release position when the closing force is relieved.

The invention has other objects and advantages as will appear in connection with the accompanying drawings in which Fig. 1 is a plan view of the 10 preferred form of draft gear, partly in section; Fig. 2 is a vertical section through the axis of the gear; Fig. 3 is a sectional plan showing the gear under compression; Figs. 4 and 5 are sectional views taken respectively on lines 4—4 and 5—5 of 15 Fig. 2; and Figs. 6, 7, 8, 9, 10, 11, 12, 13 and 14 are perspective views of component parts of the gear.

The draft sills 1 may be of usual construction. They carry front draft lugs 2, and rear draft lugs 3. The draft gear, inclusive of the follower 4 20 thereof, is located between the inner and outer pairs of draft lugs and is enclosed by the yoke 5. This yoke and the members enclosed thereby are supported by the draft gear carrier 6. The coupler 7 has its inner end in contact with the 25 draft gear follower and is attached to the yoke by the draft key 8, which passes through the sills.

The draft gear includes a spring housing 9, which preferably encloses an outer coil spring 10, constituting an application spring, and an inner 30 coil spring 11, constituting a release spring. At the open end of the spring housing is a friction housing 12, attached to the spring housing by rivets 13 or other suitable fastening means. Members 9 and 12 together constitute a load sus- 35 taining column member and may be made integral although the construction illustrated is preferable. The friction housing 12 has the interior surfaces of the two opposite vertical sides in the form of arcuate sections of cylinders, the axes 40 preferably converging toward the inner end of the housing. The other two sides are preferably straight and are provided with lugs 12'. Friction shoes 14 are disposed within the friction housing. Each shoe has its outer side of cylindrical form adapted to contact with the cylindrical surfaces of the friction housing. Each opposite side of each friction shoe is provided with a wedging formation or surface that is inclined to the axis of the cylindrical side. The inner end of 45 each friction shoe is pressed upon by the outer coil spring 10. Adjoining the friction shoes are wedge blocks 15, each having a wedging surface on one side contacting with the wedging surface of one of the friction shoes. The opposite side 50 of each of the wedge blocks is a plane surface

parallel to the axis of the gear. The outer end of each wedge block is adapted to contact with the follower and the inner end is in contact with the inner coil spring 11.

Normally stationary friction plates 16 are in 60 contact with the plane surfaces of the wedge blocks and have capacity for relative movement in the friction housing limited by engagement of shoulders 12^a on the plates with the lugs 12' and also by keys 17 which extend through the 65 plates and through the upper and lower walls of the housing 12, the slots 17^a in the plates being of greater width than the keys. Between the stationary friction plates is a central friction block or member 18. In the released position 70 as shown in Figs. 1 and 2, the inner end of the block 18, is in contact with the outer coil spring, while the outer end is spaced a short distance from the draft gear follower. The wedge blocks 15, are held in assembly in the housing by a 75 keeper 19, which spans the inner ends of plates 16 and central friction block 18, and extends into slots 15', in the wedge blocks 15. This means of assembly dispenses with projections on the wedge blocks to retain them in position, the ma- 80 chining or grinding of the friction surfaces being facilitated.

In the operation of the draft gear, forces transmitted from the coupler in buffing or pulling, set up pressure between the follower plate and the 85 wedge blocks 15. Part of this force is transmitted to the inner coil spring 11, and part is transferred through the wedging surfaces to the friction shoes 14. The inward movement of these 90 shoes is resisted by the outer coil spring 10. The resistance of the outer coil spring sets up a wedging force which produces pressure on the friction surfaces as the parts move inward and this is augmented by the relative movement between the wedge blocks and friction shoes caused 95 by the taper of the friction housing. At the beginning of the movement of the friction shoes and wedge blocks, the stationary friction plates 16 and the central friction block move inward without shifting relatively to the wedge blocks 100 until the shoulders 12^a on the stationary friction plates 16 come in contact with the lugs 12' on the friction housing. As soon as contact is established between the stationary friction plates and the lugs 12', the inward movement of the 105 stationary friction plate and the central friction block is arrested and the resistance of the gear becomes increased by the development of frictional resistance between the wedge blocks and the stationary friction plates. After the 110

draft gear follower has moved inward a distance equal to the clearance in released position between the stationary friction plates and the lugs 12', plus the clearance between the follower and the central friction block 18, such follower comes in contact with the central friction block which thereafter moves inward as actuated by the follower. As soon as the central friction block commences to move relatively to the stationary friction plates, the frictional resistance of the draft gear is further augmented.

From this description of the operation of the draft gear, it will be noted that at the initial movement frictional resistance is set up only between the friction shoes and the friction housing, this resistance being increased in stages as the friction surfaces of the wedge blocks and of the central friction block come into action.

When the force tending to compress the draft gear is relieved, the force of the outer and inner coil springs acts to return the friction members to released position. At the beginning of the release movement the friction shoes 14, wedge blocks 15, stationary friction plates 16, and central friction block 18, move outward as a unit without relative movement between any of the parts until the clearance between the keys 17 and the openings in the stationary friction plates is taken up. When the outward movement of the stationary friction plates is arrested, the force exerted by the inner coil spring serves to move the wedge blocks outward, overcoming the friction between the wedge blocks and stationary friction plates. A short additional outward movement of the wedge blocks and friction shoes brings the outer coil spring in contact with the central friction block. Thereupon, part of the force exerted by the outer coil spring is absorbed in overcoming the frictional resistance of the central friction blocks. Consequently, the force exerted by the outer coil spring against the friction shoes which tends to set up pressure on the surfaces of the friction members is decreased and release of the parts is facilitated.

Changes may be made without departing from the invention.

Having thus described my invention, I claim:

1. A friction draft gear including a friction housing; a group of friction members within said housing inclusive of friction shoes and a pair of wedge blocks in wedging relation with said shoes and further inclusive of a friction means interposed between said members; a keeper cooperating with the friction means and connecting one pair of friction members; means for keying certain of the friction members to the housing, a spring opposing the inward movement of said members; and a spring pressing on the wedge blocks and tending to force them to release position.

2. A friction draft gear including a friction housing; a group of friction members within said housing inclusive of friction shoes and a pair of wedge blocks in wedging relation with said shoes; a friction producing means interposed between said members and including outer and inner plates; a lug on the housing limiting the movement of the friction producing means in one direction and a key limiting the movement of the outer friction plates in the opposite direction; a spring opposing inward movement of said shoes; and a spring pressing on the wedge blocks to force them to release position.

3. In a friction draft gear, a housing, a pair of shoes in frictional and wedging engagement

therewith, a pair of wedge members cooperating with said shoes, and an additional friction producing means located between said wedge members and including relatively movable outer and inner plates of which the outermost are in frictional engagement with the wedge members and of which the innermost is slidable in frictional engagement with the outermost, said outermost plates being formed with slots, and keys passing through said slots and anchored to the housing.

80

85

4. In a friction draft gear, a housing, a pair of shoes in frictional and wedging engagement therewith, a pair of wedge members cooperating with said shoes, and a sequentially energized additional friction producing means located between said wedge members and including relatively movable plates of which the outermost are substantially fixed with respect to the housing and in frictional engagement with the wedge members and of which the innermost is slidable in frictional engagement with the outermost, and means connecting the wedge members and spanning said plates.

90

95

5. In a friction draft gear, a housing constituting a load sustaining column member, a pair of shoes having wedging engagement therewith, wedge blocks located inwardly of and cooperating with said shoes, and an additional resistance means located between and cooperating with the wedge blocks and including a pair of outer plates and an interposed plate, said interposed plate being slidable, said outer plates being formed with vertically extending slots, and keys anchored to the bottom and top of the housing and passing through said slots.

100

105

6. In a friction draft gear, a housing constituting a load sustaining column member, a pair of shoes having wedging engagement therewith, wedge blocks located inwardly of and cooperating with said shoes, and an additional resistance means located between and cooperating with the wedge blocks and including a pair of outer plates and an interposed plate, said interposed plate being slidable, said outer plates being formed with vertically extending slots, and keys anchored to the bottom and top of the housing and passing through said slots, said keys being of less width than the slots to enable said outer plates to move to a limited extent in a longitudinal direction.

110

115

7. In a friction draft gear, a housing constituting a load sustaining column member, a pair of shoes having wedging engagement therewith, wedge blocks located inwardly of and cooperating with said shoes, and an additional resistance means located between and cooperating with the wedge blocks and including a pair of outer plates and an interposed plate, said interposed plate being slidable, said outer plates being formed with vertically extending slots, keys anchored to the bottom and top of the housing and passing through said slots, and lugs on the inside of the housing engageable by said outer plates and serving as abutment means to take the end thrust thereof and relieve the strain on said keys.

120

125

8. In a friction draft gear, a housing constituting a load sustaining column member, a pair of shoes having wedging engagement therewith, wedge blocks located inwardly of and cooperating with said shoes, and an additional resistance means located between and cooperating with the wedge blocks and including a pair of outer plates and an interposed plate movable relatively to one another and with respect to the wedge blocks, and means cooperating with said outer plates for

130

135

140

145

150

limiting movement thereof with respect to the housing.

9. In a friction draft gear, a housing constituting a load sustaining column member, a pair of 5 shoes having wedging engagement therewith, wedge blocks located inwardly of and cooperating with said shoes, and an additional resistance means located between and cooperating with the wedge blocks and including a pair of outer plates 10 and an interposed plate movable relatively to one another and with respect to the wedge blocks, said outer plates and interposed plate being movable inwardly as an assembly with the wedge blocks for a portion of the travel of the gear, 15 and means cooperating with said outer plates and the housing for limiting the inward movement of the former whereby the wedge blocks may move relatively thereto for the remainder of the travel of the gear.

20

10. In a friction draft gear, a housing constituting a load sustaining column member, a pair of shoes having wedging engagement therewith, wedge blocks located inwardly of and cooperating with said shoes, and an additional resistance means located between and cooperating with the wedge blocks and including a pair of outer plates 80 and an interposed plate movable relatively to one another and with respect to the wedge blocks, and means carried by the housing and cooperating with said pair of outer plates and enabling them to move with the wedge blocks for a portion of the travel of the gear and then 85 for holding the plates stationary while the wedge blocks move with respect thereto during the remainder of the travel of the gear.
